(57) **CLAIM**

The ornamental design for a transfer chamber, as shown.

DESCRIPTION

FIG. 1 is a top perspective view of a transfer chamber of the present invention;
 FIG. 2 is a perspective view showing substantially the top of a transfer chamber of the present invention;
 FIG. 3 is a perspective view showing substantially one side of a transfer chamber of the present invention;
 FIG. 4 is a perspective view showing substantially another side of a transfer chamber of the present invention;
 FIG. 5 is a perspective view showing substantially one end of a transfer chamber of the present invention;
 FIG. 6 is a perspective view showing substantially another end of a transfer chamber of the present invention; and,
 FIG. 7 is a perspective view showing substantially the bottom of a transfer chamber of the present invention.
